UNITED STATES PATENT OFFICE

2,443,890

INTERNAL-COMBUSTION ENGINE

Prudent Brun, Royalton, Minn., assignor, by direct and mesne assignments, of one-fourth to Euphrosine Anna Brun, Royalton, and one-fourth to W. Y. Henning, St. Cloud, Minn.

Application June 5, 1943, Serial No. 489,811

1. Claim. (Cl. 123—56)

1

My invention relates to high power engines of the internal combustion class with double acting pistons for use particularly as motors for aeroplanes, army trucks and tanks, as well as for railroad engines and naval and mercantile ships, and also tractors and automobiles of many descriptions.

In order to increase the power of the engine each cylinder is double acting, that is to say, that while a power impulse is received from one end of the piston, exhaust and compression is simultaneously carried out at the other end of the same piston. In this manner a great simplification in construction and an increase in power per lb. of weight is gained. In a two stroke cycle engine during one-half of a complete turn of the crankshaft, the power, exhaust and compression strokes are simultaneously executed on the two working surfaces of the piston, with the piston running in one direction; and during the other half turn of the crankshaft, another power, exhaust and compression stroke is performed on the two working surfaces of the piston, with the piston running in the opposite direction.

Another advantage of the invention resides in the fact that each piston is built as a hollow cylinder, which is open over the greater portion of the length of one side, so that the crankshaft can easily be assembled, taken out or inspected. Likewise, where a plurality of the cylinders is working on the same shaft, each cylinder can be easily removed by detaching the end covers from the cylinder block. Other advantages reside in the water cooling and in the oiling system as described in the following specification.

An embodiment of my invention is illustrated in the drawings in which—

Figure 1 is a top plan view of the preferred construction of a horizontal engine.

Figure 2 is a bottom plan view of Figure 1.

Figure 3 is an axial section through one of the pistons and the cylinder block along the line 3—3 of Figure 1.

Figure 4 is a transverse section along the line 4—4 of Figure 1, and

Figure 5 is a bottom plan view of one of the pistons.

In the drawings the same numerals refer to the same parts in all the views.

Reference numeral 10, Figure 4, indicates the cylinder block forming one unit and in which are shown three cylinder borings 12, 13 and 14 running through the engine block so as to be open at each end. A cover plate 15 and 15a is

2

provided for each end and bolted to the block 10 to make a tight joint. In each of these borings is mounted a piston 17, 18 and 19 with the usual packings 20 near each end to prevent gas escape. Each piston has two working surfaces as clearly indicated in Figure 3, where piston 18 is shown at the end of the stroke to the left, leaving a small space for compressed combustion gas as at 21, while a large space as at 22 is to be seen at the right end, after completion of a power stroke, in the left hand direction of the arrow X.

The double stroke of each piston is communicated through a connecting rod 24 to a common crankshaft 25 carried transversely to the axis of the piston beneath the cylinder block 10, to which it is secured by bearing caps 26 and bolts 27. Each connecting rod 24 is carried at one end to oscillate on a pivot pin 28 held in bearing lugs 29 projecting inwardly from the upper wall 30 of each hollow piston, see Figure 3. This connecting rod 24 is of elbow shape, reinforced at the bend, instead of being of the usual straight kind. The bottom wall of the piston is cut away to provide an opening of sufficient width and length as at 31 to permit the arrangement of the crank at the required relatively small distance from the axis of the cylinder and piston and the reciprocation of the connecting rod.

The elbow shape of the rod 24 permits a direct single connection between the double piston 17, 18, or 19 and its crank 25 on the crank shaft and a power transmission in which the angle between the crank and the line of connection joining the two power transmission points on the piston and on the crank respectively does not differ materially from the corresponding angles in the customary crank and rod connections, notwithstanding the unilateral and eccentric arrangement of the connection rod joint with respect to the cylinder axis and to the plane of symmetry. This arrangement with an open piston bottom also permits of easy inspection and removal of connecting rods and crankshaft when necessary. It also facilitates lubrication from the underside as the cylinder lubricating slot 32 can easily be reached from the bottom to apply the lubricant.

The pistons are assembled in the cylinder block or removed therefrom by taking off one or both of the end caps or cover plates 15. For water cooling the cylinder block is provided with cooling spaces 33.

The crankshaft carries at one end a balance wheel, which may serve as a belt sheave or pulley 35 and at its other end means for controlling

the cam shafts 36 and 37 for a set of valves 38 and 39.

The combustion fuel supply and the exhaust for the burnt gases may be of any suitable construction and, not being part of the present invention, need not be described in detail. One inlet and one exhaust valve is as usual needed at each end of a piston for its cylinder in a four stroke cycle engine. The drawings show one exemplification of the same.

The controlling means for the valves are here indicated as sprocket wheels and chains 40 and 41, but link connections or gears and pinions may be utilized. In order to insure smooth running an odd number of cylinders and pistons with staggered crankshaft connections is necessary; three cylinders being here shown, which number may be increased to five, seven or more.

Inlet pipes 45 and 46 leading to on common manifolds 43 and 44 supply combustion gas to the valve chambers 47 and 48 with conduits 49 and 50 leading to the respective ends of each cylinder, Figures 1 and 3. Paired with the inlet pipes for each of the pistons are provided exhaust pipes 51 and 52 on manifolds 53 and 54. These exhaust pipes also connect with the gas chambers 43 and 44 which have passages 55 and 56 respectively leading into them a suitable distance from each end of the corresponding cylinder.

The valve chambers 47 and 48 for controlling gas inlet and similar chambers for exhaust gases are each provided with a valve 38 and 39 around the spindle of which is wound a compression spring 59, 59 tending to close the respective valve. The end of each spindle abuts against the surface of a cam 61 and 62 respectively, on the cam shafts 36 and 37 which are revolvably mounted on top of the cylinder block 10 and connected to revolve synchronously actuated by the chain gears 49, 41 from the crank shaft 25. As indicated in Figure 3, the cams here both point in the same direction and as a consequence the right hand valve 39 is open for exhausting burnt gas through pipe 46 from chamber 48 and conduit 50 out of the space 22 at the right hand end of the cylinder; while simultaneously valve 38 at the other end of the cylinder is closed for exhaust in Figure 3 and another valve 38, similar thereto, is open while at the opposite end (at the right hand) another valve like 39, not here shown, is closed.

This is best shown in Figure 1 where the cam shafts for each end of the cylinder is provided with an exhaust cam 61 or 62 and an inlet cam 61a or 62a. That is to say, each of the cam shafts 36 and 37 have double the number of cams to the number of piston cylinders, which they are intended to serve and these cams must be adjusted in angular positions in order to time the opening

and closing of the valve to operate the combustion in correct sequence in each cylinder.

The invention can be applied to Diesel engines as well as electrically ignited internal combustion engines. For the latter construction spark plugs 60 and 60a are indicated in the cover plates at the ends of the cylinder.

Although merely one preferred embodiment of my invention has been described specifically it is not intended to limit the application of the invention thereto except as may be required by the scope of the claim.

Having described the invention, what is claimed as new is:

15 In a multiple internal combustion engine, comprising a plurality of open cylinders with double working surfaces at opposite ends, removable cylinder heads closing said cylinders, a single hollow cylindrical piston mounted for reciprocation within each of said cylinders, each piston being provided with piston rings near its ends, with a lubrication slot between said piston rings on one side and with a further slot on the opposite side of the cylinder, piston rod lugs arranged on the side face of piston, in a position nearer to one end of the piston than to the other end, a common crankshaft for all cylinders arranged transversely to the axis of the cylinders, in close proximity to the cylinders but eccentrically with respect to said cylinders, a number of cranks corresponding to the number of cylinders on said shaft, elbow-shaped piston rods for connecting the pistons to said cranks, the elbow-shaped piston rods of adjacent cylinders being arranged at opposite sides of the crankshaft.

PRUDENT BRUN.
